WITNESS.

J. W. Swasey

James Elliott
INVENTOR.

UNITED STATES PATENT OFFICE.

JAMES ELLIOTT, OF ELLIOTTSON, PENNSYLVANIA.

ARMOR.

1,260,167.

Specification of Letters Patent. Patented Mar. 19, 1918.

Application filed August 23, 1917. Serial No. 187,808.

To all whom it may concern:

Be it known that I, JAMES ELLIOTT, a citizen of the United States, residing at Elliottson, Cumberland county, in the State of Pennsylvania, have invented a new and useful Armor, of which the following is a specification.

The purpose of my invention is to dissipate the destructive power of the explosive 10 by the following means:—

1st. The opening of channels of less resistance for the expansion of the volume of gas liberated, thus decreasing its destructive effects.

15 2nd. Changing its direction, thus leading its path away from vital points.

3rd. Giving it work to perform.

4th. Eliminating its heat units.

20 5th. By counter explosions of lesser magnitude but under control to counteract any advantage that an offensive enemy could obtain by increasing the amount of explosives used.

6th. The lessening of the destructive effects 25 produced by the explosion of large projectiles after they have pierced armor plate.

7th. To utilize in a protective way the different conductive powers, specific heats, boiling and evaporative points of metals as well 30 as their granular structure and their relative atomic weights.

8th. To apply these principles to the defense of persons and property against all forms of explosive attacks whether on land 35 or sea or in the air.

The materials which I wish to use are such metals as lead, antimony, bismuth, tin, zinc and all others which have a lower melting and volatilization point than steel or iron or 40 other metals of common use for structural purposes in defensive work. I wish to use also alloys. As an example I will state that lead with a melting point of 610 degrees F.; bismuth at 510, tin at 445, when combined 45 in the proportion of 1—1—1 will melt at 156 degrees Fahr.

However I do not wish to limit myself to the use of only one formula as different conditions require different combinations for 50 effectiveness. In some places I wish to use a reinforcement of iron or steel rods and in other cases to use one alloy as a filler and surround it or incase it in another metal as a covering or container.

55 Protection against marine attacks requires

a quick fusing or vaporizing metal which while extracting heat in its expansion will cleave the water above it and agitate it and open a channel of escape for the confined gases thus relieving the pressure against the 60 sides of the vessel to a degree that will prevent extensive rupture.

In the accompanying drawings, Figure 1 is a section showing the application of the sheets of alloys to the plating of a ship. 65

Figs. 2 and 4 are an elevation and plan of one form of invention, and

Figs. 3 and 5, similar views, of another form.

In Fig. 1 the sheets are extended from 70 above the water line to below the bilges so as to be of service against mines as well as torpedoes and projectiles. The sheets may be arranged vertically and spaced as at 8 in Figs. 2 and 4 to rapidly conduct the 75 gases of explosion to the surface, and serving to break up the homogeneity of the water masses.

The sheets or strips 4 may be reinforced by an iron or steel rod 7 and provided with 80 openings 6 to receive an explosive, the function of which is to increase the rapidity of vaporization of the strip on explosion of the offensive charge.

The strips of alloy heretofore described 85 may be arranged diagonally and interlaced to form a lattice work as shown in Figs. 3 and 5. This form includes the reinforcing rods and explosive containers of the other form and is serviceable in making 90 roof coverings to counteract the effect of shells, aerial projectiles and hand grenades. The wire reinforcement will also serve to prevent penetration by dropping projectiles. 95

I claim:—

1. An armor plating including strips of low melting point alloy.

2. An armor plating including strips of low melting point alloy, with iron reinforcements in the alloy strips. 100

3. An armor plating of low melting point alloy having chambers provided with explosive material.

4. An armor plating, strips of low melting point alloy with iron reinforcements in the alloy strips and with chambers also in the alloy strips provided with explosive material. 105

5. An armor plating consisting of diag- 110

nally arranged interlaced strips of low melting point alloy.

6. An armor plating consisting of diagonally arranged interlaced strips of low melting point alloy having metal reinforcements in the said strips.

7. An armor plating consisting of diagonally arranged interlaced strips of low melting point alloy, the strips being provided

with chambers containing explosive material.

8. An armor plating consisting of diagonally arranged interlaced strips of low melting point alloy having metal reinforcements in the strips, the strips also being provided with chambers containing explosive material.

JAMES ELLIOTT.
